(57) CLAIM

The ornamental design for a utility glove, as shown and described.

DESCRIPTION

FIG. 1 is a back perspective view of the utility glove, showing our new design;

FIG. 2 is a front perspective view thereof;

FIG. 3 is a back elevation view thereof;

FIG. 4 is a front elevation view thereof;

FIG. 5 is a right side elevation view thereof;

FIG. 6 is a left side elevation view thereof;

FIG. 7 is a top plan view thereof; and,

FIG. 8 is a bottom view thereof.

The dash-dot-dash lines shown in the figures illustrate portions of the utility glove that form no part of the claimed design.

The dash-dash broken lines shown in the figures represent stitching and form part of the claimed design.

While a right-handed glove is shown and claimed, the right-handed glove is typically sold with a left-handed glove having a design that is a mirror image of the right-handed glove.
